UNITED STATES PATENT OFFICE.

JOHN C. HULL, OF LOCKPORT, NEW YORK.

HIGH-PRESSURE PUMP.

Application filed December 4, 1926. Serial No. 152,580.

The present invention relates to a novel motor-pump unit and to an improved pump construction and design. The pump is of the general type employed in spraying operations and is so constructed and designed for this purpose as to enable it to supply and indefinitely maintain the requisite high pressure. It is characterized by its simplicity of design, rugged construction, the logical and compact arrangement and assembly of its component parts and units and the extreme facility with which it can be adjusted and repaired. The motor-pump combination is characterized by the absence of vibration, the elimination of transmission troubles and by mutual co-operation whereby each enhances the operating efficiency of the other. These and other characteristics of the invention will be more particularly set forth in the following statement 20 of the objects of the invention and in the specification.

It is an object of the invention to provide a pump capable of maintaining a steady, even flow at high pressure under all conditions of use and which may be adjusted while so functioning, to compensate for wear, thus maintaining its efficiency.

A further object of the invention is to provide a combined motor-pump unit in which all stresses are confined within such unit and where the motor and pump otherwise contribute, each to the efficiency of the other.

It is a further object of the invention to construct a pump of a plurality of substantially complete units, each of novel design and to so assemble such units as to render each of them readily accessible for inspection, removal and repair without disturbing the remaining units.

A still further object of the invention relates to the novel disposition and arrangement of the packing for the pump plungers and to the provision of external means for adjusting the enclosed packing gland while the pump is operating at high pressure.

Another object of the invention relates to the novel construction and arrangement of the several check valves and to the means for manually correcting possible faulty operations, such as sticking of the valves, while the pump is in operation.

Other objects and advantages of the invention, some of which are incidental to the foregoing, will appear in connection with the detailed description of the structure illustrated in the accompanying drawings.

Fig. 1 is an end elevation of a motor-pump unit constructed in accordance with my invention.

Fig. 2 is a view in elevation of the opposite end of the structure shown in Fig. 1.

Fig. 3 is a side elevation of the motor-pump unit of Figs. 1 and 2.

Fig. 4 is a vertical section taken on line 4—4 of Fig. 1.

Fig. 5 is a vertical section on line 5—5 of Fig. 4.

Referring now to Fig. 1 of the drawings, it will be seen that the motor-pump unit comprises a motor or engine 1 of substantially conventional design. As herein shown the motor is of the stationary type having a cast body and base portion 2, in which journals are provided for the usual crank-shaft 3. The body casting of the motor is provided with a pair of vertical faced flanges 9 integral therewith which co-operate with corresponding flanges 10 of the pump 7. Bolts 11 are employed for securing the flanges 9 and 10 together. It is evident from the structure thus far described that the pump is secured to and supported entirely by the motor.

The pump is operated from the motor by means of pinion 5 secured to the crank-shaft 3 adjacent to fly wheel 4, which pinion meshes directly with the gear 6 which is carried by the pump operating shaft. Journals are provided in opposite sides of the motor body casting for the pump operating shaft. At its end, opposite the gear 6, the pump shaft is provided with a crank pin 12 between which and the bearing ring 13 is located a plurality of suitable anti-friction elements, such as balls, rollers or the like. The crank pin and its associated bearing ring co-act with hardened wear resisting plates 16 secured to the pump yoke 15, thus imparting a reciprocatory movement to the pump plungers which are connected to the yoke 15.

The pump structure will now be described with particular reference to Fig. 4 of the drawings. It is apparent from an inspection of this figure that duplicate pumps and plungers are provided in aligned and opposed relation and also that the suction and discharge connections are likewise in duplicate. For this reason the description will be confined to one end only of the pump, it being understood that the same is likewise applicable to the structure at the opposite end. The plunger construction comprises a tubular member 18 seated at one end upon an an-

nular ledge formed on the projection 22 of the yoke 15 and at its other end is closed by a piston head 19 providing a similar annular ledge for the reception of the tubular member. A bolt 20 passes through the head 19 and has threaded engagement as at 21 with the projection 22, whereby the parts of the plunger are held in assembled relation. The plunger operates within a cylinder casting 23 within which is arranged a suitable piston packing 24. The cylinder casting 23 is provided with radial lugs or bosses 49 for the reception of threaded bolts 29. The cylinder chamber is closed by a cylinder cup 28 arranged with its open edge in abutting relation with the cylinder casting and secured in this relation through the instrumentality of the afore-mentioned bolts 29 which pass through apertured bosses on the cylinder cup. It is essential that some means be provided for adjusting the packing 24 in order to compensate for wear and to this end a packing gland 25 is provided within the chamber formed by the cylinder casting and cylinder cup. The packing gland is of tubular form and of a diameter to receive the plunger therein. The inner end of the packing gland abuts against the outermost ring or layer of the packing 24, while the outer end thereof is closed and is provided with a depression for the reception of the end of an adjusting screw 26. The body of the gland is provided with a plurality of longitudinally extending elongated slots for the passage 35 of the solution therethrough. The screw 26 is threaded through the cylinder cup 28, a suitable stuffing box 27 being provided to prevent leakage. The cylinder casting 23 is provided with suction and discharge ports 51 and 50 respectively which register with discharge and suction check valves 32 and 33 respectively. The suction valve 33 also registers with an opening in the suction chamber 30, while discharge valve 32 has an opening 40 in its upper end registering with an opening in the pressure or equalizing chamber 31. The radial bosses 49 of the cylinder casting are provided with threaded apertures for the reception of bolts 35 and 36 respectively 45 which pass through apertured lugs on the discharge and suction chambers respectively. The equalizing chamber 31 is in the form of an elongated cylinder, closed at its ends and provided midway of its length with a vertical cylindrical extension opening at one end into the main cylinder and having its opposite end closed. A suitable pressure indicating device is located in the top of the vertical cylindrical portion. The outlet or discharge opening 44 of the air chamber may be connected directly to the spray hose if desired, but in accordance with the present invention, the solution is passed through intermediate connections to be hereinafter described.

55 The suction chamber 30, as hereinbefore

described, has openings at its opposite ends registering with the respective suction valves at opposite ends of the pump, and at a point intermediate its ends is provided with a supply connection 48. Formed integrally 70 with the suction chamber on the upper surface thereof, is a guide lug 43 adapted to contact with a guide lug 42 on the pump yoke 15 for preventing oscillation of the yoke about the axis of the plungers and for otherwise enhancing the stability and smoothness of operation of the device.

The construction of the several check valves employed in the present pump construction as well as the relation of these valves with the 80 cylinders and pressure and suction chambers respectively, forms an important feature of the invention. The valves are the ball type and comprise a body portion 55, ball seat 38, gasket 39 and ball 40. The body portion is in 85 the form of a cage, with inwardly projecting ribs for receiving the ball and holding the same in spaced relation to the sides and top thereof. The valve seat is constructed separately in the form of a metallic washer and 90 is adapted to be inserted between the bottom surface of the valve body and the part with which the valve is associated. In the case of the discharge valves the ball seats 38 are located between the bottom surface of the valve 95 body and the cylinder casting while as to the suction chamber the ball seats are interposed between the valve body and such chamber.

Referring now to Figures 1, 2 and 3, it will be seen that the discharge port 44 is connected 100 by means of a pipe 45 with the cooling hopper 8 of the engine. A separate chamber is provided within the cooling hopper through which the discharged solution circulates and from which the solution is drawn through 105 pipe 45'. Duplicate hose connections 46 are provided at the end of pipe 45' for the connection of two hose lines, a shut-off valve being provided for rendering one or both of such connections inoperative. The circulation 110 of the discharge solution through the cooling hopper of the engine serves the two-fold purpose of maintaining the solution at the desired temperature and also of keeping the water in the cooling hopper at a substantially even temperature.

In order to avoid inconvenience and delay caused by faulty valve operation, externally operable releasing means are provided for quickly unseating the ball valves should they 120 become stuck for any reason. This means is in the form of a thrust rod 37 projecting through an aperture in the suction chamber in alignment with the valve. A suitable adjustable stuffing box is provided for preventing 125 leakage around the rod. It will be readily seen that by thrusting the rod inwardly its inner end will come into contact with the valve ball and dislodge the same from its seat.

Suitable facilities may be provided for lubricating the working parts of the pump. As shown, adjustable grease cups 46' are threaded into the cylinder castings adjacent to the piston packings for keeping the latter well lubricated. In some instances it may be found necessary or desirable to lubricate the co-acting parts of the crank pin and pump yoke and for this purpose a lubricant retaining casing may be constructed around these parts. In the event such a casing is provided it should be connected to or formed integral with the opposed cylinder castings, a suitable bearing for the pump crank shaft being provided in a wall thereof.

Simplicity of design is perhaps the most outstanding feature of the present invention. The cylinder castings constitute the body around which the pump is assembled. The four bolts at each end of the pump structure furnish the only securing means necessary for holding the suction chamber, the pressure chamber and cylinder cups in assembled relation. Attention is directed to the fact that the several valves are simply interposed between their respective cylinders and chambers and held in place by compression and without special securing means. By reason of this construction and arrangement of parts, the task of assembling or disassembling the complete pump is an extremely simple one. Moreover, all parts are readily accessible and removable for replacement or repair. The valves are capable of removal by simply loosening one or two of the bolts and without disturbing the remaining parts. Access may be had to the piston packing by removal of the cylinder cup, or such packing may be adjusted while the pump is in operation by means of the end adjusting bolts.

It will be observed that the manner in which the pump and motor are secured together provides a simple and compact motor-pump of substantially unit construction. By reason of the pump operating shaft and engine crank shaft being journaled in the same casting and directly geared together, a substantially vibrationless transmission is afforded. This latter feature is of considerable advantage over prior constructions employing a pump and motor mounted on separate bases with power transmitting connections extending between them.

In describing the present invention, use has been made of a single specific structure for illustrating an embodiment thereof, but it should be understood that many changes and variations in the structure shown can be made without sacrificing the advantageous features or departing from the spirit of the invention. For example, it is apparent that the present pump structure may be combined with other types of motors than that herein shown. It should also be understood that such features of the pump as the driving con-

nections, the piston construction and the size and proportions of the various parts may be varied as desired, all within the scope of the invention.

Having fully described the invention and pointed out the salient features thereof, what is claimed as new and desired to be secured by Letters Patent is:

1. In a device of the character described, and in combination with a motor having a frame and a power shaft extending transversely of said frame and journaled therein, of a pump secured directly to a side of said motor frame and driving connections from said power shaft to said pump, said connections comprising a second shaft journaled in the frame and disposed in parallel relation with said power shaft, inter-meshing gears on corresponding ends of the two said shafts whereby to drive the second shaft from the power shaft, and a driving connection between an end of the second shaft and said pump.

2. In a mechanism of the character described, the combination of an internal combustion motor of the stationary type, having a frame casting and a crank shaft journaled transversely thereof, a vertical faced flange integral with said frame casting at a side thereof, a pump having a complementary flange and means for securing said flanges together, whereby to support said pump on said frame casting, a pump operating shaft journaled in said frame casting and geared to said crank shaft, and operative connections between said pump and pump shaft.

3. In a mechanism of the character described, the combination of an internal combustion motor of the stationary type, having a frame casting and a crank shaft journaled transversely thereof, a pair of vertical faced flanges integral with said frame casting, one disposed near each end and adjacent the side wall thereof, a multi-cylinder pump having vertical faced flanges complementary to the aforesaid flanges, means for securing said flanges together whereby to support the pump on the motor, a second shaft journaled in said frame casting and having geared connection with said crank shaft, and means for operating said pump from said second mentioned shaft.

4. In a mechanism of the character described, a combined pump and motor unit having means for driving the former from the latter, a hopper for the reception of a cooling medium for the motor, a discharge conduit for the pump, and means for producing mutual interaction between the cooling medium and the contents of said discharge conduit.

5. In a mechanism of the character described, a combined pump and motor unit having means for driving the former from the latter, a hopper for the reception of a cooling medium for the motor, means for discharging

- a spray solution from the pump, and means for producing mutual interaction between the cooling medium and the spray solution by passing one through the other.
5. 6. In a spraying equipment, the combination of a motor, a spray pump, means for driving said pump from said motor, a cooling medium for said motor, means for discharging a spray solution from said pump, and 10 means for bringing said cooling medium and spray solution into heat transferring relation.
7. In a spray pump construction, an open ended cylinder casting, a radial flange at one 15 end of said casting, a cylinder cup abutting and secured to said flange, a pressure chamber, a valve interposed between said cylinder and said chamber, and means secured to said chamber and said flange for clamping said 20 valve in place and holding said cylinder, chamber, and valve in assembled relation.
8. In a device of the character described, horizontally opposed cylinders, opposed plungers within said cylinders, a yoke connecting said plungers, means for operating the yoke, a suction chamber communicating with each of said cylinders, a guide on said suction chamber, and a co-operating guide lug on said yoke, whereby movements of the yoke 25 and connected plungers may be effectively guided and oscillatory movement of the yoke prevented.
9. In a device of the class described, a cylinder having suction and discharge ports therein, suction and pressure chambers having ports registering with the suction and discharge ports respectively of said cylinder, means for drawing the said chambers towards said cylinder, and check valves interposed 30 between the respective chambers and cylinder and in alignment with the said ports, said check valves being held in position solely by compression.
10. In a machine of the class described, the combination with an engine of the stationary type having a hopper for the reception of a cooling medium for the cooling system of the engine, of a spray pump mounted on and driven by said engine, and means associated 35 with said pump and hopper for passing the spray solution from said pump through the cooling medium in said hopper, whereby to bring the spray solution to the desired temperature and to keep the cooling medium at a substantially even temperature.
11. A pump structure comprising a body portion consisting of a cylindrical packing chamber, an annular chamber having inlet and discharge openings therein, and a radial end flange; a cylinder adapted to be detachably secured to said end flange and having communication with said annular chamber, packing elements disposed in said packing chamber, and a piston reciprocable in said cylinder.
12. A pump structure comprising a body portion consisting of a cylindrical packing chamber, an annular chamber having inlet and discharge openings therein and a radial end flange; a cylinder adapted to be detachably secured to said end flange and having communication with said annular chamber, packing elements disposed in said packing chamber, a cylindrical shell of skeleton form concentrically disposed within said cylinder, 75 one end of said shell abutting the said packing elements, means extending through said cylinder and adapted to engage the opposite end of said shell for adjusting the same and a piston reciprocable in said cylinder. 80
13. A pump structure comprising a casing forming the body of said pump and to which the remaining elements of the pump are adapted to be detachably secured, said body being formed with a packing chamber, a fluid chamber having inlet and exhaust ports and a radial end flange; a cylinder adapted to be detachably secured to said flange in axial alignment with said packing chamber, and a piston reciprocable in said packing 85 chamber and cylinder. 90
14. A pump structure comprising a casing forming the body of said pump and to which the remaining elements of the pump are adapted to be detachably secured, said body being formed with a packing chamber, a fluid chamber having inlet and exhaust ports and a radial end flange; a cylinder adapted to be detachably secured to said flange in axial alignment with said packing chamber, supply and discharge manifolds associated with said pump body, check valve units interposed between said body and said manifolds, means associated with the respective manifolds and engageable with the aforesaid, a flange for drawing the said manifolds toward said body, thereby holding said valve units in place, and a piston reciprocable in said packing chamber and cylinder. 95
15. A pump structure comprising a casing forming the body of said pump and to which the remaining elements of the pump are adapted to be detachably secured, said body consisting of an elongated sleeve having one end formed with an inwardly directed flange, 100 an outer annular wall secured to but radially spaced from said sleeve, forming therewith an annular fluid chamber, said outer wall extending longitudinally beyond the adjacent end of said sleeve and having formed on its free end a radial flange, said outer wall having inlet and discharge ports formed therein for placing said fluid chamber in communication with a source of fluid supply and a receiving chamber; a cylinder adapted to be detachably secured to the radial face of said last-mentioned flange; annular packing elements disposed within said sleeve, means for compressing said packing elements against the said inwardly directed flange, and a piston 105 110 115 120 125 130

reciprocable in said cylinder and engaged by said packing elements.

16. A pump of substantially the character defined in claim 15, in combination with supply and discharge manifolds associated therewith, check valves interposed between and directly engageable with the respective manifolds and the pump structure for placing the

same in operative communication, and means associated with the respective manifolds and engageable with said last mentioned flange for clamping said pump, manifolds, and check valves in assembled relation.

In testimony whereof I affix my signature.

JOHN C. HULL.
